UNITED STATES PATENT OFFICE.

JOSEPH UNDERATION, OF HOCKING, IOWA.

CLOTHESPIN.

Application filed September 10, 1925. Serial No. 55,532.

To all whom it may concern:

Be it known that I, JOSEPH UNDERATION, a citizen of the United States, residing at Hocking, in the county of Monroe, State of Iowa, have invented certain new and useful Improvements in Clothespins; and I do hereby declare the following to be a full, clear, and exact description of the invention, such as will enable others skilled in the art to which it appertains to make and use the same.

This invention relates to new and useful improvements in clothes pins, and particularly the class of kerfed wooden pins.

15 A great difficulty in the use of the kerfed pins has been that one or the other of the legs thereof breaks off, thus rendering the pin useless.

The principal object of the present invention is to provide a means for encircling the clothes pin whereby to prevent splitting thereof.

Another object is to provide a device of this character which is simple in construction, and which has means for retaining the same in proper position on the pin, and against any tendency toward slipping therefrom.

Other objects and advantages will be apparent from the following description when taken in connection with the accompanying drawing.

In the drawing:

Figure 1 is an elevation of a clothes pin having the invention applied thereto.

Figure 2 is an enlarged horizontal sectional view on the line 2—2 of Figure 1, passing through the band.

Figure 3 is an enlarged perspective view of the band, removed from the pin, and in the position assumed when on the pin.

Figure 4 is a plan view of the band.

Referring particularly to the accompanying drawing, 10 represents the body of the wooden clothes pin, which is kerfed at 11, to provide the clothes line straddling legs 12. Pins of this type often split so that one or the other of the legs 12 is broken away from the pin body, thus rendering the pin useless.

50 Various means have been provided for pre-

venting the splitting of these pins, but they generally require some special grooving, or other treatment of the pin to adapt them for use in connection with pins of this type. Also, such previous devices have a tendency to become loosened, or completely detached from the pin, thus destroying their utility.

The present device comprises an elongated comparatively narrow band of metal 13, in one end of which is formed an opening 14, while a short tongue 15, is struck up from the other end of the body, and directed longitudinally thereof, toward the first end of the body. The body is provided with a small nail opening 16, intermediate its length, and a similar opening 17 adjacent, and inwardly of the opening 14. In the tongue 15, and in the body, outwardly of the opening 14, are formed the nail openings 18 and 19, respectively, these openings being adapted to register, when the band is properly engaged around the clothes pin, so that a single nail 20, may pass therethrough, and into the body of the pin, just inwardly of the inner end of the kerf.

In assembling the parts, the band is passed around the body of the pin, so that the tongue carried end is beneath the other end. The tongue is first disposed to extend outwardly from the body, so that it may readily enter the opening 14, when the band is drawn around the pin. The tongue is then bent to extend in the direction of the end of the body which is provided with the opening 14, and pressed against the body so that its openings registers with the opening 19, after which a small nail is passed through these openings and driven into the body of the pin. Nails are then driven into the body of the pin through the openings 16 and 17. The band is thus held against slipping longitudinally of the clothes pin, and also from movement around the pin. Furthermore, the binding effect of the band, at the point where the pin usually splits, effectively prevents such splitting, and lengthens the life of the pin.

What is claimed is:

The combination with a kerfed clothes pin, of a device for preventing splitting of

the pin comprising a band engaged around the body of the pin adjacent the kerf thereof, the band having an opening in one end, and a second opening between the said end and said first opening a tongue in the other end of the band directed toward the first end thereof and engaged through said first opening and extending toward the first open-

ing said tongue having an opening registering with the second-named opening of the band, and a fastening means engaged through the opening of the tongue and the second-named opening of the band and into the body of the clothes pin.

In testimony whereof, I affix my signature.
JOSEPH UNDERATION.
